UNITED STATES PATENT OFFICE.

JOHN F. HAWLEY AND FRED L. MOSS, OF CHILlicothe, MISSOURI.

RAILWAY-CROSSING SIGNAL.

1,244,204.

Specification of Letters Patent. Patented Oct. 23, 1917.

Application filed April 6, 1916. Serial No. 89,414.

To all whom it may concern:

Be it known that we, JOHN F. HAWLEY and FRED L. Moss, citizens of the United States, residing at Chillicothe, in the county of Livingston and State of Missouri, have invented certain new and useful Improvements in Railway-Crossing Signals, of which the following is a specification.

This invention relates to railway crossing signals and has as its object to provide a signal which will constitute an effective warning both during the day and at night and in which the day and night signals may be selectively rendered active at will 15 of the person whose duty it is to attend to the said signals.

It is another aim of the invention to provide in a signal of this class a novel arrangement of the signal post and the signals 20 thereon as well as a novel arrangement of switches which may be manually operated so as to render either or both of the signaling devices operative.

It is another aim of the invention to provide in connection with the signal device an annunciator so constructed as to indicate whether or not the visible or the audible signal, or both, was given at the time of 25 passage of a train past the crossing so that in the event of an accident or wreck the responsibility may be determined.

In the accompanying drawings:

Figure 1 is a perspective view of the crossing signal embodying the present invention.

Fig. 2 is a view in elevation of the signal post illustrating the arrangement of the visible and audible signals thereon.

Fig. 3 is a diagrammatic view of the 40 wiring.

Fig. 4 is a detail vertical sectional view through the circuit closing device which is disposed beneath the track rails.

In the drawings the track rails are indicated by the numeral 1 and Fig. 1 illustrates in a general way a crossing at one side of which is mounted a post or other suitable support indicated by the numeral 2. As clearly shown in Fig. 2 of the drawings, the post is provided at its upper end with an arm 3 carrying one or more electric lights 4 constituting a visible signal designed to be employed chiefly at night, these lights being supplied with electricity 45 through conductor wires 5 which are led upwardly through insulators 6 secured upon one side of the post 2. The numeral 7 in- dicates an electric bell and the numeral 8 indicates wires which are led upwardly through insulators 9 upon the opposite side 69 of the post and to the said bell which constitutes the audible signal designed to be chiefly employed during the day, although it may be employed also at night in conjunction with the visible signal. At a suitable point a switch 10, as for example, an ordinary snap switch, is interposed in the wires 5 which lead to the electric light bulbs and this switch may be manipulated so as to cut the visible signal into and out 70 of service. In a like manner a snap switch 11 is interposed in the wires 8 and may be manipulated to cut the audible signal into and out of service, and these switches 10 and 11 are preferably secured upon the post 75 2 and are, of course, adapted to be independently operated. The preferred arrangement of wiring is illustrated in Fig. 3 of the drawings, although it will be understood that this may be varied as found 80 desirable. In this figure that one of the wires 5 in which the snap switch 10 is interposed leads to one terminal of a battery 12 which may be arranged at any convenient point and from the other pole of this battery 85 leads a wire 13 which is connected electrically to one contact of the circuit closing device which is arranged beneath the rail at one side of the crossing. This device will presently be specifically de- 90 scribed. A wire 14 is connected electrically to the other contact of the circuit closing device which in the said figure is indicated generally by the numeral 15. This wire 14 is connected to the other one of the wires 5 95 and also to one of the wires 8 and is further connected electrically to one contact of the other circuit closing device which is arranged at the other side of the crossing. A wire 16 leads from the other contact of 100 the last mentioned circuit closing device to one terminal of a battery 17, the other terminal of which battery is connected by the other one of the wires 8 to the electric bell 7, the switch 11 being interposed in this last 105 mentioned wire 8. A wire 18 bridges the wires 5 and 8 between the batteries and the annunciators. It will now be apparent by reference to the diagrammatic view that when either of the circuit closers 15 has its 11 contacts brought into engagement by depression of the rail beneath which the circuit closing device is disposed and, of course, through the weight of the train

passing over the rail, the circuit will be closed through the visible signal 4 or the audible signal or through both signals, depending upon the positions of the switches

5 10 and 11.

Referring now to Fig. 4 of the drawings, it will be observed that the circuit closing device comprises a lower casing section 19 having an attaching flange 20 whereby it 10 may be secured upon one of the ties supporting the rails 1 and this casing section is open at its upper end and has telescopically fitted thereto an upper casing section indicated by the numeral 21, the upper 15 closed end of which latter section bears against the under side of the rail, the sections being held in a direction toward separation by means of a spring 22 housed within the sections and bearing at its lower end 20 against the bottom of the section 19 and at its upper end against the under side of the top of the section 21. Arranged within the sections and surrounded by the spring is a sleeve 23 which may either be loosely disposed in place or integral with the bottom of the section 19, as shown in Fig. 4. Within the lower end of the sleeve 23 is arranged a block 24 of insulation supporting a spring contact finger 25 which has electrically connected to it the wire 14. A block 26 of insulating material is mounted upon the under side of the top of the casing section 21 and supports a contact finger 27, the free ends of the fingers 25 and 27 being normally spaced but being adapted to be brought into mutual contact upon downward movement of the casing section 21 against the tension of the spring 22 upon depression of the rail 1 due to passage of a train over the said rail.

40 As before stated, it is one aim of the invention to provide in connection with the visible and audible signals, an annunciator device which will automatically indicate whether or not the visible or audible signal, 45 or both, was given at the time of passage of a train past the crossing so that in the event of an accident or wreck the responsibility may be determined, and in the drawings the annunciator for the audible signal is indicated by the numeral 30 and the annunciator for the visible signal by the numeral 31, the annunciator devices being arranged within a casing 32 which is preferably mounted upon the post 2, although, if desired, it may 50 be located at some other convenient point. It will be observed by reference to Fig. 3 that the annunciators 30 and 31 are respectively interposed in the wires 8 and 5.

As stated above the annunciators 30 and 55 31 are designed to indicate whether or not the visible or audible signal or both was

operated at the time of passage of a train and therefore it will be understood that each of these annunciator devices is so constructed as to register the closing of the respective 65 circuit in which it is located and that any device capable of performing this function will serve the purpose.

It will be understood, of course, that the contact devices such as shown in Fig. 4 of the drawings may be placed beneath the rail as shown in this figure or so arranged that the upper section 21 of the casing will be presented at the tread of the rail so as to be directly engaged by the wheels of the 75 train as they pass the said device.

Having thus described the invention, what is claimed as new is:

1. In a railway crossing signal system, a pair of train operated circuit closers adapted to be disposed one at either side of a crossing, a pair of distinctive signals adapted to be disposed near the crossing, electrical means for selectively actuating either or both of the signals upon the closing of either circuit closer, manually controlled means governing the selection of the electrical means, and means for indicating the actuation of either or both of the signals even after the circuit closer causing such actuation has been 90 opened.

2. In a railway crossing signal system, a multiple circuit having parallel portions and a common portion, a source of electrical energy and a normally open train operated circuit closer in the common portion, distinctive signals one in each of the parallel portions, means for selectively rendering either or both of the parallel portions active with the common portion, and means for indicating actuation of either or both of the signals even after the energizing circuit has been opened by the circuit closer.

3. In a railway crossing signal system, a multiple circuit having a pair of parallel portions and a pair of portions each common to both parallel portions, a source of electrical energy and a normally open train operated circuit closer in each common portion, distinctive signals one in each of the 110 parallel portions, means for selectively rendering either or both of the parallel portions active with both common portions, and means for indicating which of either or both of the signals has been actuated even 115 after the actuating circuit closer has been opened.

In testimony whereof we affix our signatures.

JOHN F. HAWLEY. [I.S.]
FRED L. MOSS. [I.S.]
